United States Patent Office

Des. 175,459
Patented Aug. 30, 1955

175,459

HOT FOOD TRUCK OR SIMILAR ARTICLE

John Morris Carter, Dallas, Tex.

Application March 14, 1955, Serial No. 35,027

Term of patent 7 years

(Cl. D14—3)

Figure 1 is a front perspective view of a hot food truck or similar article showing my new design.

I claim:

The ornamental design for a hot food truck or similar article, substantially as shown.
